UNITED STATES PATENT OFFICE

CHESTER A. THOMAS, OF CHICAGO, ILLINOIS, ASSIGNOR TO BABSON MANUFACTURING CORPORATION, OF CHICAGO, ILLINOIS, A CORPORATION OF ILLINOIS

DESIGN FOR A HENHOUSE

Application filed May 23, 1930. Serial No. 35,736. Term of patent 14 years.

To all whom it may concern:

Be it known that I, CHESTER A. THOMAS, a citizen of the United States, residing at Chicago, in the county of Cook and State of Illinois, have invented a new, original, and ornamental Design for Henhouses, of which the following is a specification, reference being had to the accompanying drawing, forming a part thereof.

Referring to the drawings:

Figure 1 is a front perspective view of a hen house, showing my new design. Figure 2 is a rear perspective view thereof, on a reduced scale.

My present invention relates to a hen house wherein the front and rear walls of the hen house slope inwardly and upwardly and the roof slopes from the upper edge of one wall to the upper edge of the other wall. The sloping front and rear walls, in effect, form a part of the roof of the building.

I claim:

The ornamental design for a hen house as shown and described.

CHESTER A. THOMAS.
